(74) Attorney, Agent, or Firm—Marshall, Gerstein & Borun

(57) CLAIM

The ornamental design for a “stem for bath accessory items”, as shown and described.

DESCRIPTION

FIG. 1 is a front and left side perspective view of a stem for bath accessory items showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof, the bottom being a mirror image of that shown;

FIG. 7 is a front and left side perspective view of a second embodiment thereof;

FIG. 8 is a front and left side perspective view of a third embodiment thereof showing my new design;

FIG. 9 is a front elevational view thereof;

FIG. 10 is a top plan view thereof, the bottom being a mirror image of that shown;

FIG. 11 is a front and left side perspective view of a fourth embodiment thereof showing my new design; and,

FIG. 12 is a front elevational view thereof.

The broken-line disclosure in the views is for illustrative purposes only and forms no part of the claimed design.
